Reynolds & Cook,
ATTORNEY

UNITED STATES PATENT OFFICE.

ADOLPHUS G. ADAIR, OF SEATTLE, WASHINGTON.

NUT-TURNING TOOL.

1,329,571.

Specification of Letters Patent.

Patented Feb. 3, 1920.

Application filed December 16, 1918. Serial No. 267,041.

To all whom it may concern:

Be it known that I, ADOLPHUS G. ADAIR, a citizen of the United States, and resident of the city of Seattle, county of King, and State 5 of Washington, have invented certain new and useful Improvements in Nut-Turning Tools, of which the following is a specification.

My invention relates to pneumatic motor 10 devices and consists of certain improvements to pneumatic motors designed to better adapt them for certain special purposes.

The objects of my invention are two-fold; first, to provide an attachment for 15 pneumatic motors, whereby they may be used to better advantage in such work as turning up nuts; and second, to provide means whereby the application of air to drive such 20 motors is automatically controlled by the torque which is communicated to the handles by which the machine is held in place.

The features of my invention, which I 25 deem to be novel, will be first described and then particularly defined by the claims. In the accompanying drawings I have shown my invention embodied in preferred constructions.

Figure 1 is a side view of a motor showing 30 a portion of a driven gear in section.

Fig. 2 is an enlarged detail of that one of the handles through which the air for operating the motor is conveyed, illustrating the manner of automatically controlling the 35 supply of this air.

Fig. 3 is an end view of the gear at the end of the motor casing.

Fig. 4 is a cross section through this handle.

40 In the drawings, 1 represents a pneumatic motor, such as is quite widely used for reaming and boring holes, and such other devices wherein the work is of a rotative character. The casing of such a motor is usually provided with handles, as 2, whereby the same is handled and controlled. Usually the air for operating the motor is supplied through one of these handles, which for this purpose is a tube.

45 Within this handle is a valve mechanism by which the air is controlled and this valve is controlled through the medium of a sleeve or like member, 3, which is mounted on the outside of the tube so that it may be turned.

50 One way of doing this is to employ a diagonally positioned slot 30 in the sleeve and

a pin 31 entering said slot and connecting in some way with the valve, by which the air is controlled. As the particular construction of the valve for doing this work 60 conforms no part of my invention I have not illustrated the same in detail.

As a part of my invention I have provided means whereby the control of this valve is automatically secured through the lateral 65 swing or torque given to the handle 2 by the resistance of the tool being operated by the device. To the handle 2 is secured a spring bar 4. Preferably this is secured at each end, as by the use of U-bolts 40. The central portion of this spring bar is preferably held normally at a little distance from the handle 2.

Carried by the spring bar 4 is a finger or arm 5 which extends over and against the 75 side of the rotative sleeve 3, through which the valve is controlled. This sleeve is provided with a pin 32 which is engaged by the forked end of the finger 5, so that if the bar 4 be pressed toward the handle 2, the 80 sleeve 3 will be turned in such direction as to shut off the supply of air.

In using a device of this sort it is common to have one of the arms engage the body of the workman and in this way to 85 resist the turning effect communicated thereto by the resistance of the tool being operated thereby.

The spring 4 will be of sufficient strength that it will not be bent enough to close off 90 the air until this torque exceeds the desired strength. If, however, from any cause, as a sudden sticking of the tool, this torque should suddenly rise above a safe point, the spring 4 would be suddenly pressed inward 95 or toward the handle 2 and this would result in immediately turning the sleeve 3 and thus cutting off the supply of air. The device thus works effectively as an automatic stop and safety device.

100 For some kinds of work, as for turning up heavy nuts, the device as ordinarily constructed, is both lacking in strength and otherwise not as well adapted for this purpose as desired. To cure this I have provided a special head 6, which bolts on to the casing as a substitute for and in the same manner as the ordinary head. This head has a central boss 60, through which projects a shaft 61, which represents the tool receiving shaft of the ordinary construction. Instead, however, of this shaft having secured

thereto some means for holding a tool, it has secured thereto a small pinion 62.

At one side of the head 6, substantially in line with the outer side of the casing 1, is a boss 63, in which is journaled a shaft 64. This shaft has secured thereto a gear wheel 7. This gear wheel preferably is an internally toothed wheel and meshes with and covers the pinion 62. The shaft 64 is provided with a socket 65, or other means by which the tool, which is to be used, may be secured thereto. I have herein shown a socket wrench extension 8 as secured thereto. As thus illustrated the device is adapted for turning up nuts.

By reason of the above modifications of construction, the motor is able to exert a heavier turning effect upon the nut and also by reason of the fact that the shaft 8 is placed over to one side of the casing, it will be possible at times to use it in places where otherwise it could not be conveniently used. Further, the position of the gear wheel 7, makes it serve as a cover and protection for the pinion 62.

What I claim as my invention is:

1. The combination with a power driven hand tool having a rotative tool holding member and handle bars extending outwardly from the axis of rotation thereof, of

a power cut-off device and a spring bar carried by one of said handle bars and having a controlling connection with said power cut-off device, whereby the power will be automatically cut-off by a super-normal torque. 35

2. The combination with a power driven hand tool having a rotative tool holding member and handle bars extending outwardly from the axis of rotation of said tool, of a power cut-off device, a spring bar 40 extending alongside of and normally spaced from one of the handle bars and means connecting the said spring bar with the power cut-off device to cut off the power by the engagement of said spring bar with the body under a super-normal torque.

3. The combination with a pneumatic motor device of the class described, of an air controlling valve mechanism having a rotative sleeve mounted upon a handle and 50 means connecting said sleeve with the valve to control it, a spring bar extending lengthwise of and secured by its ends to said handle with its central portion spaced away from the handle, and an operative connection from said spring to the valve controlling sleeve.

Signed at Seattle, King county, Washington, this 10th day of December, 1918.

ADOLPHUS G. ADAIR.
